UNITED STATES PATENT OFFICE.

RALPH RAGAN, OF ATLANTA, GEORGIA.

ROTARY PUMP.

1,224,567.

Specification of Letters Patent.

Patented May 1, 1917.

Application filed February 5, 1916. Serial No. 76,367.

To all whom it may concern:

Be it known that I, RALPH RAGAN, a citizen of the United States of America, and a resident of Atlanta, Georgia, have invented 5 certain new and useful Improvements in Rotary Pumps, of which the following is a specification.

One feature of the invention disclosed herein relates to that class of rotary pumps especially adapted for high duty, whether 10 gas or liquid which comprise a rotor, having suitable impellers mounted thereon, and a valve member coöperating therewith, the rotor and the valve member rotating within 15 a suitable housing, and it consists in mounting the impellers for radial movement in the rotor whereby the outer faces of the impellers may be kept in contact with the walls of the impeller chamber, and in making 20 such outer faces of such length that their forward ends will seat against the walls of the impeller before the rear ends pass out of contact with the valve element, whereby contact with the wall of the chamber or 25 with the valve element is insured at all times to prevent slippage. This also avoids the necessity of the use of stops to limit the outward movement of the impellers.

Another feature of this invention consists in so mounting the impellers of a rotary pump that they will be thrown outwardly against the housing by centrifugal force or by the back pressure of the fluid, or by both combined.

35 A further object is to provide a washer for the rotary element of a rotary pump having means whereby such washer is held against the sides of the rotary elements as wear occurs between these parts, to prevent 40 slippage.

It further consists in the construction, arrangement, and combination of the parts of which it is composed, as will be hereinafter more fully described and claimed.

45 Referring to the accompanying drawings in which corresponding parts are designated by corresponding marks of reference,—

Figure 1 is a central transverse section through a pump embodying my invention.

50 Fig. 2 is an elevation thereof with the cover removed.

Figs. 3 and 4 are views similar to Fig. 2, but with the washer shown therein removed, showing successive positions of the 55 parts.

The pump housing 1, has a circular chamber 2, and a second chamber 3, having at least a part of its wall circular, the two chambers being connected to each other by a throat 4, less in width than the diameter 60 of the chamber 2. A plate 5 is bolted upon the chambered face of the housing and forms a cover for the chambers.

The housing and cover plate are suitably strengthened in line with the centers of 65 chambers, and form bearings 6 for the shafts 7 and 8. The shaft 7 thus supported at the center of the chamber 2 has keyed thereto the rotor 9, while the shaft 8, supported at center of the chamber 3 has the 70 valve element 10 keyed thereto.

An induction port 11, and an eduction port 12 are formed in the housing on the opposite sides of the line joining the centers of the two shafts, preferably at the 75 throat 4. Supplemental eduction ports 12^a may be provided close to the center line to prevent the formation of a vacuum at that point.

The shafts 7 and 8 are geared together by 80 the gears 12 and 13, and motion may be imparted thereto in any suitable manner, as through the shaft 8, so that the rotary members move past the eduction port toward the induction port as indicated by the arrows, 85 in Figs. 3 and 4.

The rotor 9 consists of a circular casting whose diameter is less than that of chamber 2, whereby an annular space 14 is left between the rotor and the walls of 90 the chamber, and has a thickness from side to side less than the depth of the chamber 2.

One or more radial slots 15 are formed in the periphery of the rotor, in each of 95 which snugly fits the stem 16 of an impeller 17. The head of the impeller has its outer surface of considerable length and struck on an arc whose radius is the same as the radius of chamber 2, such outer surface being if desired, connected to the radial faces of the stem by faces 18 inclined to the radii on which they are located. The thickness of the impellers should be the same as the rotor, and their stems should fit 100 within the slots with sufficient freedom to move outwardly therein under the centrifugal force due to their speed and weight (the latter of which is increased by their enlarged head) until their curved outer faces 110

bear against the circular walls of the chamber 2, and against the valve element as will be described.

The valve element 10 is likewise in the 5 form of a cylinder and is of the same thickness as the rotor. Its diameter is such that it fits snugly against the rotor, and also against the circular portion of the wall of the chamber 3 in which it is contained. It 10 is provided with one or more peripheral recesses 19 to receive the heads of the impellers. The bottom of each recess 19 is an arc struck from the center of the valve element with such a radius that when a 15 recess is on the line of centers its bottom is at a distance from the center of the rotor equal to or less than the radius of the rotor chamber.

The ratio between the gears 12 and 13 20 is such that the intermesh between the impellers and the recesses is obtained and the length of the impellers is such that the forward or rear end of an impeller is against the base of the corresponding recess before its rear or forward end has left contact with the circular wall of the rotor chamber 2 at the point where such wall is 25 interrupted by the throat 4. The first stated position is shown in full lines in Fig. 4, and the second position in dotted lines thereon. In a suitable recess 21 formed in the wall of the chamber 3, may be located an arc-shaped packing 22, pressed by a spring 23 against the peripheral wall of 30 the valve element.

Within the recesses 2 and 3, and bearing 35 on the outer sides of the rotor and valve element is located a washer 25, which is suitably apertured for the passage of the shafts 7 and 8, and which may be strengthened by the webs 26. The washer is thus 40 between the cover 5 and the rotary elements, and is pressed against the latter by springs 27-27^a contained in the continuous groove 45 28 in the walls of the chambers 2 and 3 at the outer or cover ends thereof. The outer wall 29 of this groove is tapered outwardly and upwardly. The springs are in the form of a split ring 27, and a part ring 27^a, the 50 former being seated in that part of the groove which is formed in the walls of the chamber 2, and the latter in that part formed in the wall of the chamber 3. Each of these rings has a beveled face 28^a, corresponding in inclination with the wall 29 55 of the groove, and as the rings are inserted in place while under compression, and have their lower faces resting on the washer 25, they will, when released, exert a wedging 60 action to hold the latter against the impeller and valve element, and thus hold the latter against the base of the chambers 2 and 3 even though wear occur in the contacting surfaces. Thus leakage past the 65 ends of the rotor is prevented.

The general scheme of operation of a structure such as described is obvious, viz., that fluid contained in the annular space 14 is driven by the impeller 17 forwardly and out of the eduction port, the space in 70 the rear of the impeller being in turn filled by fluid entering through the induction port, but particular attention is directed to the following.

As the impellers are movable radially, 75 they will, for reasons stated herein, be held at their outward limit against the circular walls of the rotor chamber as long as their angular position around the center thereof permits such contact. Thus slip is prevented. As and before the rear end of an 80 impeller passes from the wall of the rotor chamber at the throat thereof, its forward end entering the recess 19, and rocking on, and in contact with the base thereof in 85 passing the line of centers, and after passing such line its forward end bears upon the wall of the rotor chamber at the other side of said throat, before the rear end of the impeller leaves the recess. The 90 construction here shown permits the parts to be machined to accomplish this, and at the same time prevents the pump being put out of commission by wear and use. For 95 this purpose the impellers preferably subtend a greater arc than is subtended between the apex of the walls of the two chambers, and the line of centers of the chambers. As the contact between the impellers and the wall of the rotor chamber 100 is a sliding one, more wear will take place in such walls than on the base of the recess, which has a rolling contact with the impeller face. Thus, after use, the base of the recess may project slightly within the 105 circle of the walls of the impeller chamber, but this is taken care of by the radial movement of the impeller, and it will be seen in such a case, that the pressure side of the impeller will be separated from the suction side thereof by contact between the 110 impeller and the valve-element. It will also be seen in such a case that in moving on the wall of the rotor chamber again, this last named contact is maintained until the impeller passes from off the valve element and is allowed to move outwardly against the wall of the rotor chamber. Thus the outward movement of the 115 impellers is at all times controlled by surfaces 120 coöoperating with their curved outer faces, dispensing with the use of special stops.

The inclined faces 18 on the impeller, when given the slope shown, serve by the reaction of their thrust upon the fluid, to 125 forcibly hold the outer arc-shaped faces of the impeller against the parts coöperating therewith. As however, under certain speeds of rotation it may be that centrifugal force will be so great as to cause exces- 130

sive friction between the impellers and the walls of the chamber 2, I may, if I so desire, reverse the inclination of such inclined faces so that the radial component of the 5 thrust reaction is inwardly, instead of outwardly. A face suitable for this purpose is shown at 18^a.

As a supplemental means for controlling the radial pressure on an impeller, I may 10 mount in a suitable chamber in the rotor, a weight 30 connected to the impeller by a lever 31 of the first order. The elements of this structure may be such as to reduce 15 to any desired degree, the effected action of centrifugal force on the impeller.

Having thus described my invention what I claim and desire to secure by Letters Patent is,—

1. In a rotary pump, the combination 20 with a housing containing connected chambers, of a driven rotor and valve element contained in the said chambers and having their peripheries in contact, of a recess in the periphery of the valve-element, and a 25 radially movable impeller on the rotor entering said recesses and whose outer face bears on the wall of the inclosing chamber, and is of such length as to bear on such wall before it leaves such recess.

2. In a rotary pump, the combination 30 with a housing containing connected chambers, of a driven rotor and valve element contained in the said chambers, and having their peripheries in contact, of a recess 35 in the periphery of the valve-element, the base of the recess being struck from the center of rotation of the valve element, and a radially movable impeller on the rotor whose outer face is struck from the center 40 of rotation of the rotor and which on entering the recess in the valve-chamber bottoms therein before its opposite end leaves the wall of the rotor chamber.

3. In a rotary pump, the combination 45 with a housing containing connected chambers, of a driven rotor, and a valve element contained in said chambers and having their peripheries in contact, of a recess in the periphery of the valve element, the base 50 of the recess being struck from the center of rotation of the valve element, and a radially movable impeller on the rotor whose outer face is struck from the center of rotation of the rotor, and subtends a greater 55 arc than the arc between the line of centers of the chamber and the junction of their walls.

4. In a rotary pump, the combination with a housing containing connected chambers, of a driven rotor and valve element 60 contained in the chamber and having their peripheries in contact, of a recess in the periphery of the valve element, and a radially movable impeller on the rotor whose outer face is struck from the center of 65 rotation of the rotor and which, on entering the recess of the valve chamber and after leaving the wall of the rotor chamber, is limited in its outward movement by the bottom of the said recess. 70

5. In a rotary pump, the combination with a housing containing connected chambers, of a driven rotor and valve element contained in the said chambers and having their peripheries in contact, of a recess in 75 the periphery of the valve element, and a radially movable impeller on the rotor whose outer face bears on the bottom of the recess when fully therein, and is of such a length to bear on such bottom before it 80 leaves the wall of the rotor chamber.

6. In a rotary pump, the combination with a driven rotor and its inclosing chamber, the rotor having a peripheral slot 85 therein, and an impeller mounted to slide in such slot, and having an impelling face formed at an angle to the radius on which it is situated so that the reaction of the impulse thrust has a radial component.

7. In a rotary engine, the combination 90 with a rotor and its inclosing chamber, of an impeller mounted on the rotor for radial movement and subjected to centrifugal force due to movement of the rotor, and a centrifugal member also mounted on the 95 rotor and coupled with the impeller to reduce the centrifugal pressure acting on the impeller.

8. In a rotary pump, the combination 100 with a housing having intersecting chambers therein provided with a groove in the outer ends of the walls thereof, of rotary members contained in such chambers, a washer located in the outer end of such chambers outside of the rotary members, 105 and spring rings seated in the said groove, the rings and groove being each provided with coöperating inclined faces against which the expansible force of the rings is exerted to hold the washer against the rotary elements. 110

In testimony whereof I have signed my name.

RALPH RAGAN.
